(57) **CLAIM**

The ornamental design for a tortilla warming apparatus, as shown.

DESCRIPTION

FIG. 1 is a top plan view of a tortilla warming apparatus showing my new design with the door open;

FIG. 2 is a top plan view thereof with the door closed;

FIG. 3 is a front elevational view thereof with the door open;

FIG. 4 is a front elevational view thereof with the door closed;

FIG. 5 is a rear elevational view thereof with the door closed;

FIG. 6 is a perspective view thereof with the door open; and,

FIG. 7 is a right side elevational view thereof with the door closed; and,

FIG. 8 is a left side elevational view thereof with the door closed.

The portions shown in broken lines in all views are for illustrative purposes only and form no part of the claimed design.
